[52] U.S. Cl. 40/65; 40/78.07

[57] ABSTRACT

[51] Int. Cl. G09f 11/30

A device for holding the cards of a pack, and positioning them individually in succession substantially in an enclosed means, exposing the faces to view in a window, first the front faces, followed by the reverse faces, of all of the cards in the pack, in a recycling of the cards which continues until device is stopped.

KINETIC CARD VIEWING DEVICE

This invention relates in general to devices using media which bear communicable effects for display in sequential order for visual recognition, and more particularly to devices wherein the media used are cards.

To my knowledge, the invention pioneers the conception of devices using cards wherein in a potentially endless continuity of recycling the faces of the cards come into position in a window for viewing, individually in succession, first the front faces, followed by the reverse faces, of the cards in the pack.

A significant attribute of my invention is a card cartridge which is insertable into, and removable from, the device, and ready for operation in the device upon insertion.

The cards require no holes to effect their movement as the drive mechanism involved is either of a kind which effects movement of the cards by pushing it by its lower butt end, or by having it drawn against a moving belt by air suction.

Likewise no holes are involved in the cards if the inputs of data concepts are provided by means of indicia printed in a magnetic encoding ink in conjunction with their application to photo-electric means. However, where the inputs of data concepts involve electro-mechanical means, the indicia are implemented by holes punched out of the card substance of a shape to make them applicable to one face of a card to the exclusion of its other face.

A significant application of the invention is in the educational field covering devices for the presentation of data in such a way as to stimulate student interest. Applications include the hidden answer method for cramming in school examinations. In this connection, the device provides ingenious signaling means for directing the student in his problem solving, and provides means for scoring performance. The techniques which thus find application in the educational field, also have application in the entertainment field covering games for which a wide variety of programs may be developed.

It has application in a device for improving reading skills. Such a device may be provided with speed regulators to establish the number of words read in a given period of time.

The invention has application in a device for use as a mechanized book, such as is provided in a dictionary, wherein cards which have been data-punched for built-in sensing means provide for automatically locating a specific card, turned to the applicable face from among the cards in a pack, which contains a word or term on which information is sought. Other similar applications include use of the device as a telephone directory, a catalog, a price list, cookbook, etc.

The invention fills a need in a device for the presentation of sheet music in sequential order for reading by the performer without requiring him to handle the sheets while engaged in the execution of music. In this connection, timing controls may be provided to enable him to regulate or preset the device to his requirements. Another similar application involves cards which present a musical composition in a single horizontal arrangement of musical graphics.

Likewise it provides for a device using cards which bear copy of communicable matter for delivery in talks and sermons, with means provided in the device, controlled by the speaker, for keeping movement of the

copy past a viewing window held to his speed of delivery.

To summarize: The invention covers devices using cards constituted as reading and teaching machines, data processing machines, mechanized books and entertainment machines. In addition, the device may be adapted for use as a camera, photographic copying machine, or a machine for projecting graphical effects upon a screen.

OBJECTIVES OF MY INVENTION

Objectives of my invention are to provide in its basic materialization in a kinetic card viewing device specific characteristics as follows:

- a. A device driven by one of two different means, viz.:
  - 1. Manual means;
  - 2. Electrical means.
- b. A device provided with a card drive means of one of three different types, viz.:
  - 1. A belt drive holding card by vacuum (air suction);
  - 2. A worm drive holding card by its lower butt end;
  - 3. A twin worm drive with cams, which holds card by its lower butt end.
- c. A device manifested in either of two versions, viz.:
  - 1. A portable version which is compact and easy to handle;
  - 2. A fixed installation version for large-scale operation.
- d. A device provided with one of two types of card receptacle means, viz.:
  - 1. A fixed card receptacle means, providing for the manual insertion and removal of cards;
  - 2. A cartridge means which contains a pack of cards, with said cartridge readily insertable into, and removable from, the device, and when in device, to operate coordinatively with aspects in the device which are interdependent with it.
- e. A device provided with the means to endow it with one of the patterns of card movement from among the following, viz.:
  - 1. A continuous forward reading speed of full card lengths;
  - 2. A stop-and-go sequence for equi-sized divisions of full card lengths;
  - 3. Wherein in (2) above, a high-speed go aspect is followed by a time interval dwell which is either:
    - i. Selective;
    - ii. Fixed.
  - f. A device provided with a window to expose each cardface for viewing in one of the following five ways:
    - 1. In its entirety;
    - 2. In a fractional part, equal to one of the parts into which cardface is divided along its length to which its is in registry;
    - 3. In a series, wherein one or more cardfaces are continually exposed for viewing, aligned to form a single band of graphical effects in movement;
    - 4. Same as (3) above, except that a multiplicity of bands is provided wherein a mask set against the window exposes a selected band for viewing to the exclusion of the other bands;
    - 5. In a reduced width, to provide a marginal portion for accommodating indicia contained therein.
  - g. A device provided with a pilot card, wherein, upon completion of the play of a face-side of the cards in the pack, the pilot card conveys this condition by means of

a visual signal, and brings the device to a stop through means provided in connection therewith.

h. A device provided with a score registry means in connection with its use as a teaching, game or entertainment machine.

j. A device provided with the means to sense data concepts through indicia provided in the cards to produce data outputs therefrom, in accordance with the requirements established therefor in each particular design application.

Other objectives and a fuller understanding of the invention may be had by referring to the specifications and the claims hereinafter presented, to be taken in conjunction with the illustrations included therewith.

The Cards in a Pack

The cards comprising a pack for use in the device have face-sides of rectangular shape with their butt ends squared, with the pack of the dimensions to fit into the card receptacle means in the space provided so that the cards can undergo the required movement therein, allowing a minimum increment of space for clearance of the cards by their width and length, and keeping the number of cards at the maximum at which they will not bind, thus for the cards to exert sufficient pressure against the front and rear walls of the card receptacle means that each successive forwardmost card in the pack is held flush against the front wall of the card receptacle means, thus, preceding the initiation of a card drive cycle, for card to be in required vertical alignment with the card contact aspect of card drive means that said aspect faces lower butt end of card squarely, with the upper butt end of card aligned to card egress orifice, thereby for card to clear said orifice without impediment in the action of the card drive means upon the card to move it out of the card receptacle means.

The cards should be produced from a good quality bristol or tag stock possessed of a fair degree of flexibility.

A measure of practicability of the device lies in the fact that both faces of each card are utilized, and that in a number of design concepts presented herein each cardface is utilizable in its entirety.

Operation of the device starts with the series of the faces of the cards in a pack facing forward, followed by the series facing rearward thereto.

BRIEF DESCRIPTION OF THE DRAWINGS

FIG. 1-A illustrates the paging arrangement of the cards in ascending order, in the front-face series, pages 1 to 100 inclusive, and in the back-face series, pages 101 to 200 inclusive;

FIG. 1-B illustrates the cards and direction of card movement;

FIG. 2 presents an example of a card taken from a pack, which has the graphical matter in its two faces applying to a teaching method;

FIG. 3 presents a cross-sectional side view of the device;

FIG. 4 presents a view of the lower part of a version of the device provided with a built-in card receptacle means designed for the manual handling of the cards;

FIG. 5 presents an enlarged cross-sectional top view of the card drive means;

FIG. 6 presents an enlarged cross-sectional side view of the card drive means;

FIG. 7 presents a rear view of the device showing viewing window;

FIG. 8 presents a cross-sectional front view of the device, showing card drive means;

5 FIG. 9 presents a cross-sectional view of the semi-cylindrical part of the card passage way means provided with a rotatable inner aspect of said means;

FIG. 10 presents a sectioned view of the device from the rear wall containing the viewing window;

10 FIG. 11 presents a sectioned side view of the device showing the card drive means;

FIG. 12 presents a view of the device centered vertically head-on to apex of card passageway means;

15 FIG. 13 presents an enlarged sectioned top view of card drive means;

FIG. 14 presents an enlarged partial lengthwise view of card drive means;

20 FIG. 15 presents a cross-sectional side view of card passageway means, viz., the position of insertion of cartridge into device, showing pilot card centered in duct of said means;

FIG. 16 presents a cross-sectional side view of upper part of card cartridge;

25 FIG. 17 presents the design of a face-side of pilot card;

FIG. 18 presents a sectioned view of the upper part of the device from the front, showing means for selecting and implementing periods of time interval dwell;

30 FIG. 19 presents a sectioned view of the upper part of the device from the side showing means for selecting and implementing periods of time interval dwell;

FIG. 20 presents a flow chart of the principal operational functions of the device;

35 FIG. 21 presents a partially sectioned front view of card drive means;

FIG. 22 presents a sectioned top view of card drive means;

40 FIG. 23 presents a cross-sectional top view of device;

FIG. 24 presents a front view of device;

FIG. 25 presents a side view of the device, partially cross-sectioned to show interior details;

45 FIG. 26 presents a view of the device, from the position as faced by the operator, partially sectioned to show the means provided for the application of power and vacuum;

FIG. 27 presents a perspective view of the device showing the viewing window and the operating controls;

50 FIG. 28 presents a card in the process of entering cartridge through two-way card-flow orifice in its front wall;

FIG. 29-A presents a card in the process of entering cartridge through two-way card-flow orifice in its rear wall;

55 FIG. 29-B presents a card in the process of exiting cartridge through two-way card-flow orifice in its rear wall;

FIG. 30 presents an enlarged partially sectioned side view of device showing card in pack in cartridge, and belt for transport of cards;

FIG. 31 presents an enlarged partial view of device through section A-A', FIG. 30;

60 FIG. 32 presents an enlarged partial view of device through section B-B', FIG. 30;

FIG. 33 presents a portion of the combination data retrieval selector aspect and card viewing window;

FIG. 34 presents a portion of a cardface in the retrieved position for viewing, with portion of the face of card which had preceded it also showing;

FIG. 35 presents an enlarged cross-sectional front view of the data retrieval means with three switches;

FIG. 36 presents an enlarged cross-sectional side view of the data retrieval means with switch in an extended (closed) position;

FIG. 37 presents an enlarged cross-sectional side view of the data retrieval means with switch in retracted (open) position;

FIG. 38 shows the data retrieval means with addition of an electrical circuit for sensing the indicia in the cardface;

FIG. 39 presents a portion of a cardface design for communications in a dialogue style in teaching;

FIG. 40 presents a view of the instrument panel of a device providing for cards designed for a system of data application for response participation of user, and providing score registry means for measuring performance;

FIG. 41 presents an enlarged view of the marginal strip of card containing the indicia, with a legend for their interpretation;

FIG. 42 is a side view of upper part of device, with facility in attachment thereto in fully extended position, as used when carrying the device;

FIG. 43 is a front view of upper part of device with facility in attachment thereto, relative to the side view presented in FIG. 42;

FIG. 44 is a side view of upper part of device, with facility in attachment thereto, adjusted into a position to put the device in an inclined position for its use as for reading;

FIG. 45 is a perspective view of device, with facility in attachment thereto, placing device in an inclined position on a horizontal surface such as a tabletop for its use as for reading;

FIG. 46 is a side view of upper part of device, with facility in attachment thereto, in retracted position for convenience in storing device;

FIG. 47 is a partial front view of upper part of device, with facility in attachment thereto in retracted position, projected relative to side view presented in FIG. 46;

FIG. 48 is a cross-sectional side view of upper part of device, with facility in attachment thereto in retracted position projected relative to views presented in FIGS. 46 and 47.

FIG. 1-A is a diagram illustrating by example the paging arrangement of the cards in a 100-card pack. In this example, the cards comprise in ascending order, in the front-face series, pages 1 to 100 inclusive, and in the back-face series, pages 101 to 200 inclusive, with the graphical effects in the series facing frontward appearing in the window from the position for viewing right-side-up, and in the series facing rearward up-side-down, relative to those facing frontward.

As each card in the back-face series turns to become a card in the series facing frontward, its face presents the graphical effects right-side-up relative to the window for viewing, as illustrated in FIG. 1-B.

The designation P.C. in a cardface, located between the end/beginning of each series of cardfaces, shown in FIGS. 1-A and 1-B, refers to the pilot card, details of which are presented in the text which follows this presentation.

FIG. 2 presents an example of a card taken from a pack, which has the graphical matter in its two faces applying to a teaching method involving a dialogue style of communication. In this example, each of the two faces is divided along the line of card movement into nine rectangular areas of equal size, for use in a device with a viewing window arranged to exhibit these areas individually in sequence starting with the rectangular area at the top.

10

The Pilot Card

The pilot card, referred in the *Abstract of the Disclosure* as the control card, functions in the operation of the device as the means to signal the end/beginning of

15 the play of a face-side of the cards in the pack. The signal thus produced indicates that the pilot card is in the duct of the card passageway means, centered therein lengthwise, a condition which provides user in the operation of a device equipped with a card cartridge with 20 three options, viz.:

a. To have the device continue operating, thus for it to proceed to play the opposite face-side of the cards in the cartridge;

b. To remove the cartridge from the device, and 25 thereupon to insert another cartridge into the device;

c. To stop operating the device.

Operability of the pilot card and the cardpack cards in the device is predicated on the condition that the duct in the card passageway means is of such appertaining length relative to the length of a card, that when it is centered in the duct, its forward butt end and its rearward butt end are in contact respectively with the rearward butt end of the card which is forward of it, i.e., the last card which has completed its entry into the cartridge, and the forward butt end of the card which is rearward of it, i.e., the forwardmost card in the cardpack, with their opposite butt ends in contact with the card baseplane in cartridge.

30 It is to be noted that in any division of the face of a card into a series of rectangular segments for viewing, an odd number thereof is to be used in order to provide for the pilot card a centered position in the duct of the card passageway means upon completion of the play of a face-side of the cards in the pack.

45

The Card Cartridge

The receptacle means containing a pack of cards, which is insertable into, and removable from, the device, is herein referred to as a card cartridge. The cards are in stacked arrangement therein with their front faces facing the wall thereof referred to as its front wall.

50 In design concept B of device, access to the cartridge for its insertion into, and removal from, the device is provided in means for taking hold of the cartridge by two fingers of one hand through a semi-circular opening in two opposite walls of the device as shown in FIGS. 10 and 12, reference 67.

55 The cartridge is insertable into, and removable from, the device when the pilot card is centered in the duct of the card passageway means, as shown in FIG. 15. This condition is signaled to the operator in one or more of a number of ways in which the device may be equipped to meet specific requirements, visual and/or auditory.

60 A simple way for the pilot card to signal when the device is ready for a transfer of cartridges is by means of an easily recognizable graphical effect such as a bril-

liantly colored mark on the surface of each of the two face-sides of the pilot card positioned so as to come into registry in pilot card signal window alternately for each of two plays of the cards in the pack.

The mechanics thus provided by the pilot card establishes the basis for other signaling means, as well as for bringing the device to a stop upon completion of the play of a face-side of the cards in a pack.

Introduction to Design Concepts

The kinetic card viewing device of my invention is herein characterized in specific embodiments, referred to as design concepts A, B, C, D, E, F, G, H and J. They are each presented separately in the specifications.

The first six of the nine design concepts enumerated are as follows:

a. Design concept A, a manually operated version of the device, represents the simplest form in which the invention can generally be manifested; it represents the starting point in the schematic exposition of developments therefrom as incorporated in the specifications;

b. Design concept B represents an electrically operated version of the device, derived from design concept A, provided with a time delay control to effect a time interval dwell of a card upon completion of each card drive movement, wherein either a fixed card receptacle means or a card cartridge is provided, involving operational aspects as follows:

1. In a fixed card receptacle means, access to the cards is provided through an opening in the bottom of the device;

2. In a card cartridge, an opening is provided in a side wall of the device for its insertion and removal in a path perpendicular to the direction of card flow between the cartridge and the card passageway means; (The specifications relate only to (2), as (1) above may easily be developed from the information presented in (a) for design concept A);

c. Design concept C, a version of the device which is similar to design concept B except that upon completion of each card-drive movement a timer controlled card dwell is brought into play;

d. Design concept D is an electrically operated version of the device, similar to design concept B except that movement of the cards is effected by a card-drive means controlled by two worm gears of inverted matching design, each provided with a cam aspect to regulate the movement of said means;

e. Design concept E represents an electrically operated version of the device, derived from design concept B, wherein the cardfaces bear communicable matter confined to a continuously evolving horizontal band of graphics for viewing uninterruptedly in movement;

f. Design concept F is an electrically operated version of the device, in which a moving belt is used as a card transport means against which the cards are held by vacuum (air suction).

Design concepts G, H and J are electrically operated versions of the device, derived from design concept B into which punched card data processing functions have been incorporated. These design concepts are as follows:

a. Design concept G, which provides for the retrieval of a card for the applicable face bearing desired data concepts, commanded from among the cards in a pack;

b. Design concept H, which provides for data inputs programmed into a card, for the applicable face, to ef-

fect data outputs to register in means provided to supply user of the device with auxiliary data in connection with data contained in cardfaces in graphical effects for visual recognition;

c. Design concept J, which provides for response participation between device and user of the device, involving communicable matter in a dialogue style of exposition, for teaching and entertainment, and in games programmed into cards for outputs constituting responses to inputs, augmented by score registry means for measuring performance.

The specifications which follow for each of the aforementioned design concepts provide for the inclusion of a card cartridge and a pilot card as part of the design. For design concepts A and B consideration is also given to a variation involving the use of a build-in card receptacle means.

Design Concept A of Kinetic Card Viewing Device, a Manually Operated Version of the Invention

Design concept A is that of a manually operated version of the device composed solely of the basic elements which constitute the means for positioning each card in a pack individually in sequence for viewing. These elements comprise:

- a. A pack of cards;
- b. A card receptacle means;
- c. A card passageway means;
- d. A card drive means.

FIGS. 3 through 9 present design concept A of device. The illustrations refer, except for FIG. 4, to the adaptation of design concept A to the use of a card cartridge. FIG. 4 relates to a build-in version of the card receptacle means involving the use of a card access plate.

The illustrations relating to the cartridge type also serve to help visualize the built-in type of card receptacle means. This requires merely the substitution for the walls of the cartridge and of the device proper which adjoin, a single wall, retaining the side-wall of the cartridge exposed to the outside to constitute part of the device structure, and substituting for the lower part of the cartridge, access plate 23, FIG. 4, using gripping means 24 for taking hold of the access plate.

Refer to FIGS. 3 through 9 illustrating design concept A, wherein:

a. FIG. 3 presents a cross-sectional side view of the device;

b. FIG. 4 presents a view of the lower part of a version of the device provided with a built-in card receptacle means designed for the manual handling of the cards;

c. FIG. 5 presents an enlarged cross-sectional top view of the card drive means;

d. FIG. 6 presents an enlarged cross-sectional side view of the card drive means;

e. FIG. 7 presents a rear view of the device showing viewing window;

f. FIG. 8 presents a cross-sectional front view of the device, showing card drive means;

g. FIG. 9 presents a cross-sectional view of the semi-cylindrical part of the card passageway means provided with a rotatable inner aspect of said means.

The keyed references in the illustrations as given in the figures, numbered 3 to 9 inclusive, range from 1 to 24 inclusive, and are as follows:

- 1 Outer wall of the device;

- 2 Card cartridge wall;
 2A Base of cartridge;
 3 Pack of cards;
 4 Card passageway means (card transfer structural aspect);
 5 Duct in card passageway means 4;
 6 Card egress orifice in card cartridge;
 7 Card ingress orifice in card cartridge;
 8 Card ingress orifice in card passageway means, aligned to card egress orifice 6 in card cartridge, providing for passage of cards from cartridge into duct of card passageway means;
 9 Card egress orifice in card passageway means, aligned to card ingress orifice 7 in card cartridge, providing for passage of cards from duct of card passageway means into cartridge;
 10 Slidable block of card drive means;
 11 Slideable block retaining means;
 12 Card drive aspect of slideable block 10;
 13 Slide control aspect of slideable block 10;
 14 Manual operating lever aspect of slideable block 10;
 15 Slideable block upper and lower limits anchors;
 16 Slot in front wall of cartridge centered to width of forwardmost card facing said front wall, of the length to provide for the card drive aspect 12 to push with its forward drive contact face against card by its lower butt end to drive card out of the cartridge and for slot to extend therefrom in a groove through top wall of cartridge to provide for the feed-in of card drive aspect into cartridge upon insertion of cartridge into the device, and for detachment of card drive aspect from the cartridge upon removal of cartridge from the device;
 17 Slot in wall of device contoured to slot 16 in cartridge, wherein through this slot and slot 16 in front wall of cartridge, card drive aspect is given access to each successive forwardmost card in cartridge.
 18 (Optional). Groove to each side of slot 16 in front wall of cartridge;
 19 Card drive starting position recess;
 20 Protrusion in rear wall of cartridge for offsetting position of card in its movement into cartridge;
 21 Card viewing window in back wall of cartridge, of transparent material, with opening in device, contiguous thereto, of corresponding measurements;
 22 Semi-circular openings in outer wall of device for manually gripping cartridge in its insertion into, and its removal from, the device;
 23 Access plate in built-in receptacle means;
 23A Rotatable drum in card passageway means;
 23B Shaft element connected to each side of rotatable drum 23A to hold it axially aligned to side walls of device;
 23C Base plane of cartridge (foundation) on which the cards stand;
 24 Semi-circular openings in outer walls of device for manually taking hold of access plate 23 of built-in receptacle means for the insertion and removal of cards.
- Card passageway means 4 constitutes a part of the general structure of the device. It is a U-shaped facility with duct 5 extending therethrough. Said duct is open at each end of the card passageway means in orifices 8 and 9, meeting respectively orifices 6 and 7 in cartridge, wherein both the orifices in the device and in the cartridge are of a size to accommodate a card of a width and thickness to pass therethrough.

- Card ingress orifice 8 in card passageway means is in registry with card egress orifice 6 in cartridge to provide for the passage of cards individually in sequence from the cartridge into the duct whereto each successive forwardmost card is discharged from the pack in the cartridge.
- Card egress orifice 9 in card passageway means is in registry with card ingress orifice 7 in cartridge, to provide for the successive passage of cards individually in sequence from the duct into the cartridge to come into position therein in back of the cards in the pack.
- This exchange of cards from the front to the rear of the pack effects for the cards inbetween a creeping movement by their lower butt ends to the front of the cartridge.
- The duct of the card passageway means is bounded:
- a. In its height, by two surfaces facing the inner and outer faces of a card as it is contained therein, said surfaces being separated from one another by a distance 20 slightly greater than the thickness of a card, to allow a card to slide therein on its faces, but not so great as to cause a card in back of another card to wedge between, or to move over or under a card ahead of it;
  - b. In its width, relative to the width of a card, to hold it properly channelized in a forward movement without appreciable side play;
  - c. In its length, an effective length equal to the length of a card.
- The card drive means consists of slideable block 10, held in retaining means 11, located centrally widthwise relative to card facing front wall of cartridge, through which position card drive means is arranged to move such distance as to expel card from its position in cartridge wherein its lower butt end is in contact with card baseplane to bring card into duct of the card passageway means, centered therein.
- Slideable block 10 consists of three functional aspects: slide controlling aspect 13, card drive aspect 12, and manual operating lever aspect 14. They are aligned to the direction of card movement in an arrangement across thereto, as shown in FIGS. 5 and 6, wherein:
- a. Slide controlling aspect 13 provides the means for keeping the block properly channelized within slideable block retaining means 11 to insure in its upward movement continual positive contact of card drive aspect 12 with lower butt end of card, and wherein top and bottom limits anchors 15 serve to hold slideable block within the required range of movement;
  - b. Card drive aspect 12 extends through slot 17 in wall of device and through slot 16 in adjoining front wall of cartridge, and into the cartridge interior a distance exceeding slightly the thickness of a card, wherein:
1. Card drive aspect engages by its forward drive contact face, card by its lower butt end, to move card out of the cartridge, and provides upon completion of said movement, for the return of the card drive aspect to the starting position recess 19; wherein:
  - i. Card drive means is provided, for the purpose of its return movement, with a sloping face from the edge of its forward drive contact face to effect in the reverse movement, a sweep of the card drive aspect between the front wall of cartridge and the outer face-side of the next succeeding card, coming to a stop in the position where the forward drive contact face of card drive aspect faces

lower butt end of card for the next ensuing movement to drive a card out of the cartridge;

2. (Optional). Groove 18 is provided in the front wall of cartridge to each side of slot 16 facing the cartridge interior, as an aid to having the card by its face be in firm contact with the surface of the front wall of the cartridge, to serve as an added means to insure that the card, relative to its upper and lower butt ends, is in alignment both with the forward drive contact face of the card drive aspect and card egress orifice 6 in cartridge;

c. Operating lever aspect 14 provides the means for manually moving the slideable block 10 upward to discharge a card out of the cartridge, and downward to return the block to the starting position of a card drive cycle.

In the return movement of the card into the cartridge, which is through the card ingress orifice 7 in card cartridge, it passes by its forward butt end protrusion 20 located on surface of rear wall of cartridge facing outer face of card, said protrusion extending from said wall surface such distance that card, as it completes its movement into the cartridge, comes into position, relative to said wall surface, such distance therefrom as to provide a space for entry behind it of the next succeeding card.

Instead of a protrusion in rear wall of cartridge, is a means which may be employed in which the lower part of the wall of the cartridge facing outer face of card entering cartridge sets forwardly relative to the plane of the upper part of said wall by a sufficient distance, to provide for the next succeeding card to enter the cartridge behind said card.

Upon discharge of card from duct of card passageway means into the cartridge in back of the cards therein, outer face of card is in full view in window 21 of cartridge, said window being of transparent material within the area of the cardface, with an open area in the device contiguous thereto of corresponding measurements.

The insertion of the cartridge into the device, and its removal therefrom, is effected through an opening in the bottom of the device. In inserting the cartridge into the device, it is brought to a positive stop, to which it is keyed to bring the two card-flow orifices in the cartridge into alignment with the two card-flow orifices in the card passageway means. When in this position, the card drive access slot 16 in the front wall of the cartridge is in alignment with the card drive access slot 17 in wall of device, thus for the contours of the two slots to coincide in providing access of the card drive aspect 12 to the cards in the cartridge.

Before the insertion of a new cartridge into the device, card drive aspect 12 extends through slot 17 in device in the position in which it had been left in the device after the last removal of a cartridge therefrom. In its insertion into the device, the cartridge is passed over the card contact part of the card drive aspect, thus for card drive aspect to become located in slot 16, through it being fed into groove which extends from slot in upper wall of cartridge.

Conversely, after card drive aspect had delivered the pilot card into the card passageway means, centered therein, cartridge is ready for removal from the device. In its removal, card drive aspect is disengaged from slot 16 as cartridge is withdrawn from the device, with card

drive aspect remaining to extend through slot 17 in wall of device.

A Version of Card Passageway Means Involving a U-turn of Short Diameter

This version of card passageway means, illustrated in FIG. 9, is particularly applicable to a kinetic card viewing device in which the cardpack is composed of only a small number of cards. It differs from the basic version presented in the specifications of which FIGS. 3 and 8 are typical, in that the inner of the two half-cylindrical aspects of the U-shaped structure is changed to provide in the card contact surfaces thereof, both a stationary half-cylindrical aspect along a marginal strip contiguous to each side wall of device, and a rotatable drum 23A inbetween, in which their respective radii are of identical measurement, and the axis of the rotatable drum is in alignment with the axes of the adjoining half-cylindrical aspects, with the drum provided with two shaft elements 23B which are rigidly affixed to each side of the drum, with the other end of each shaft element rotatably seated in a bearing in its respective side wall in device.

In this version, the card contact surface of the drum is provided with a coating of a chemical composition, such as of latex, to provide a frictional surface against which card holds by its contact face thereto as it moves through duct.

Design Concept B of Kinetic Card Viewing Device, an Electrically Operated Version Derived from Design Concept A

FIGS. 10 through 14 illustrate design concept B of device, wherein:

- FIG. 10 presents a sectioned view of the device from the rear wall containing the viewing window;
- FIG. 11 presents a sectioned side view of the device showing the card drive means;
- FIG. 12 presents a view of the device centered vertically head-on to apex of card passageway means;
- FIG. 13 presents an enlarged sectioned top view of card drive means;
- FIG. 14 presents an enlarged partial lengthwise view of card drive means.

The keyed references in the illustration as given in the figures, numbered 10 through 14, range from 25 through 70.

A description of the keyed references follows:

- 25 Enclosing walls of card drive means;
- 26 Motor and motor drive shaft for forward movement aspect of card drive nut 30;
- 27 Motor and motor drive shaft for reverse movement aspect of card drive nut 30;
- 28 Worm gear;
- 29 Intermediate motor speed regulating means (not detailed);
- 30 Card drive nut;
- 31 Gasket between motor 26, intermediate motor speed regulating means 29, and worm gear 28;
- 32 Gasket between motor 27 and worm gear 28;
- 33 Slot in front wall 34 of device;
- 34 Front wall of device (wall of device contiguous to card drive means);
- 35 Slot in front wall 36 of cartridge through which card drive means extends;
- 36 Front wall of cartridge;

37 90° forward drive contact face of card drive aspect of card drive nut 30 to effect contact with lower butt end of card to push card out of the cartridge;

38 Sloping lateral side of card drive aspect of card drive nut 30 to provide for the ready descent of card 5 drive nut to the starting position recess 42;

39 Duct of card passageway with card therein;

40 Pack of cards;

42 Card drive starting position recess;

43 (Optional). Groove to each side of slot 35 on inside surface of front wall 36 of cartridge;

44 Card drive aspect of card drive nut 30;

52 Pilot card window through which pilot card serves to signal when all of the cards in the pack are in the cartridge, constituting the condition when the cartridge 15 may be removed from the device, and another cartridge inserted into the device;

53 Pilot card switch;

64 One of the side walls of device;

66 Card viewing window in device, contiguous to 20 rear transparent wall in cartridge to provide for the viewing of a face-side of a card upon completion of the movement of the card into the cartridge in back of the cards therein;

67 Gripping access openings, of which there are two, one in each side wall of device across from one another, with cartridge inbetween, for manually gripping the cartridge;

68 Protrusion on inside rear wall of cartridge, which 30 provides for the card, as it enters cartridge through its ingress orifice, to come into position in back of the cards therein;

69 Dry-cell batteries in battery chamber for use in portable versions of a device not provided with electric 35 current by other means;

70 Access means to dry-cell batteries.

Design concept B constitutes an adaptation of design concept A to electrical means of operation. It is presented herein by its components as follows:

a. A removable receptacle means containing a pack 40 of cards referred to as a card cartridge;

b. A card passageway means with duct extending therethrough to provide the channel in which the cards move on their face-sides individually in sequence successively out of, and into, the cartridge, said card passageway means constituting a U-shaped structural aspect of the device in which each of its ends is supported against the cartridge, and wherein the orifice at each end of said card passageway means meets respectively each of two orifices in cartridge;

c. A card drive means comprising:

1. Motor 26, to effect movement of card drive nut 30 through the rotation of worm gear 28, to discharge card 55 out of the cartridge;

2. Motor 27, to effect movement of card drive nut 30 through the rotation of worm gear 28, to return said nut to the starting position for the next ensuing movement of a card out of the cartridge;

3. Worm gear 28 coupled to motors 26 and 27 to rotate alternately in the opposite direction to effect respectively the forward and reverse movement of card drive nut 30, with a clutch provided between each motor and the worm gear to absorb the overrun in the rotation of the motors to hold motor gear to its required position of stoppage upon the completion of its rotation in each direction;

4. Card drive nut 30 internally threaded to mesh with worm gear 28, and fitted to slide against the four enclosing walls 25 of card drive means, is provided with card drive aspect 44 which extends through slot 33 in wall 34 of device, and slot 35 in front wall 36 of cartridge, and therethrough into cartridge interior by a distance exceeding slightly the thickness of a card, wherein:

i. Card drive aspect 44 of card drive nut 30 is provided with a 90° forward contact face 37 whereby it pushes against lower butt end of card to drive card out of the cartridge into duct 39 of card passageway means, displacing therefrom the card which preceded it, by pushing by its forward (upper) butt end against the card which it displaces, by its rear (lower) butt end, thereby to effect the deposit of the displaced card in the cartridge in back of the cards therein;

ii. Card drive aspect 44 of card drive nut 30 is provided with an inclined face 38 contiguous to its 90° forward contact face, to provide in the reverse rotation of worm gear 28 a sliding downward movement of card drive nut between the next succeeding forwardmost card and the front wall of cartridge in its return to the starting position for the next ensuing card drive cycle;

d. Electrical means to control the operation of motors 26 and 27, wherein:

1. Motor 26 is energized to effect through worm gear 28 the forward movement of the card drive means to push card out of the cartridge, wherein, upon completion of said movement, a time delay control means provides for the deenergizing of said motor to effect a time interval dwell of card;

2. Whereupon motor 27 is energized to effect through worm gear 28 the reverse movement of the card drive means to return the card drive nut to the starting position, wherupon motor 27 is deenergized, and motor 26 is energized for the next ensuing card drive cycle.

Before the insertion of a cartridge into the device, card drive aspect 44 extends in device through slot 33 in the position in which it had been left in the device after the removal of cartridge therefrom, i.e., in the completion position of a card drive cycle.

In its insertion into the device, the upper part of the cartridge comes into a position beyond the extending part of the card drive aspect, thus for cartridge to feed said aspect through a slot which meets slot 35 at a right angle in a movement which locates said aspect in slot 35 for its movement therein.

Conversely, after card drive aspect had delivered the pilot card into the duct of the card passageway means, cartridge is ready for removal from the device. In its removal, card drive aspect is disengaged from slot 35 by way of the feeder slot, as cartridge is withdrawn from the device, with said aspect remaining to extend slot 33 in wall of device.

Depending upon user's requirement, the device may be designed for a forward reading speed and a high return speed of the card drive means through conventional means of motor and speed transmission regulators, or in place of two motors, one motor may serve both the forward and reverse movements calibrated to a high speed, with a time delay control provided to effect, upon completion of the forward movement drive,

a time interval dwell during which the card is exposed for viewing.

In cases where considerable flexibility is desired in the card dwell time, the card drive means would be confined to a single card drive cycle with each actuation of said means. The user would simply depress a button each time he is ready to view the next succeeding face-side of a card.

Design Concept B of Device Providing for the Exhibiting of each Cardface in a Succession of Rectangular Segments into which it is Divided

The exhibiting of each cardface in a succession of segmented areas involves cards in which each cardface is divided along the line of card movement into an odd number of rectangular areas of equal size, as illustrated in FIG. 2.

This arrangement requires for each card drive cycle to consist of a series of forward movements equal to the number of separate areas into which each cardface is divided, requiring a stop/time delay/start switching means in each position of division of cardface for each segment thereof to register with window.

The successive forward movements of the card drive means covering a cardface are followed by a single reverse movement of the card drive means to bring said means into position for the start of the next series of forward movements of a card covering a card drive cycle.

The card drive means provided to effect the successive movement of the cardfaces by rectangular segments is an improvement over the customary method wherein cards with holes along one of their margins are acted upon by a wheel provided with studs along its rim, which as it rotates through the action of a reciprocating lever, moves the cards.

A Pilot Card of a Design to Provide the Required Condition of Operability with Card Cartridge, in Design Concept B of Device

Design considerations involved in the application of a pilot card to design concept B of device are presented in FIGS. 15, 16 and 17, wherein:

a. FIG. 15 presents a cross-sectional side view of card passageway means, viz., the position of insertion of cartridge into device, showing pilot card centered in duct of said means;

b. FIG. 16 presents a cross-sectional side view of upper part of card cartridge, viz., the position of insertion of cartridge into device, showing aspects of accommodation between cartridge and pilot card in its centered position in card passageway means;

c. FIG. 17 presents the design of a face-side pilot card.

The keyed references in the illustrations as given in the figures, numbered 15, 16, and 17, range from 71 to 95 inclusive, and are as follows:

71 Card cartridge;
72 Cards in pack;
73 Pilot card (by itself);
74 Pilot card in duct of card passageway means;
75 Card passageway means (part of structure of device);

76 Forward widthwise edge of pilot card, relative to upper face;

77 Rearward widthwise edge of pilot card, relative to upper face;

78 Rear card in cardpack in cartridge;
79 Front card in cardpack in cartridge;
80 Groove-like aspect in card egress orifice in cartridge;

5 81 Groove-like aspect in card ingress orifice in cartridge;

82 Rear lengthwise edge of pilot card, from position of cartridge insertion;

10 83 Front lengthwise edge of pilot card, from position of cartridge insertion;

84 Point at which forward widthwise edge of pilot card tapers inward toward front lengthwise edge thereof;

15 85 Point at which rearward widthwise edge of pilot card tapers inward toward front lengthwise edge thereof;

86 Ceiling of space in device for occupancy of cartridge;

87 Signal indicium in pilot card;

88 Pilot card signal window in card passageway means;

89 Electrical switching means to act upon indicium in pilot card when a face-side of the cards in the pack has been played;

20 90 Card egress orifice in cartridge;
Card ingress orifice in card passageway means;

92 Card ingress orifice in cartridge;

93 Card egress orifice in card passageway means;

25 94 Forward directing widthwise end portion of pilot card extending out from card egress orifice 93 in card passageway means;

95 Rearward trailing widthwise end portion of pilot card extending out from card ingress orifice 91 in card passageway means.

30 35 The mechanical requirements for the pilot card for its coordination with the cartridge, set forth herein for design concept B of device, is equally applicable to any version of the device in which the space provided in device for occupancy by the cartridge is arranged for accessibility thereto in a direction which is transverse to the direction of card flow at juncture of the cartridge with the card passageway means.

The cartridge, upon having been moved into the space in device provided for its occupancy, clicks into a locked position to insure registry of elements in the cartridge with those in the device, to effect their proper coordination in the operation of the device, viz.:

a. The two card-flow orifices in the cartridge, card egress orifice 90, and card ingress orifice 92, respectively, are then in alignment with the two card-flow orifices in the card passageway means, card ingress orifice 91, and card egress orifice 93, thus constituting a channel for the flow of cards individually in sequence from the front of the cardpack in the cartridge into the card passageway means, from whence the cards move into the cartridge to align in back of the cards therein;

45 b. Card drive aspect 44 of card drive nut 30 is then in the position in which it extends into cartridge interior through slot 33 in wall of device, and slot 35 in front wall of cartridge, thereby for the card drive means to act upon the cards to drive them out of the cartridge into the card passageway means.

The Pilot Card

The pilot card required in a built-in receptacle means is of the same shape and dimensions as that of a cardpack card. However, for the cartridge version of design

concept B, and others involving a similar arrangement, it differs therefrom in order to provide an orderly feed-in of the cartridge into the device, while retaining the dimensional displacement properties of a cardpack card for its operability in the device.

Preparatory to the insertion of the cartridge into the device, pilot card is centered in duct of the card passageway means, with its rear lengthwise butt end 82 in contact with rear lengthwise curb or duct (relative to the opening into space in device for the insertion of the cartridge representing the front for the purpose of this orientation), with rearward trailing widthwise end portion 95 of pilot card extending out from card ingress orifice 91 in card passageway means, and the forward directing widthwise end portion 94 of pilot card extending out from card egress orifice 93 in card passageway means, with both end portions extending out into the space for occupancy by cartridge by an equal length, and having the ends taper off in their range from the back to the front, so that at the front they come flush with ceiling 86 of said space in device. This provision permits the two end portions of the pilot card to feed easily into the groove-like aspects of the cartridge as cartridge is inserted into the device.

FIG. 17 illustrates the shape of a face-side of the pilot card in accordance with the aforementioned requirement. In the card presented, the rear lengthwise edge 82, as well as the maximum overall width, conform to the length and width of a cardpack card.

As illustrated in FIG. 17, rear lengthwise edge 82 meets forward directing edge 76 and rearward trailing edge 77 at right angles, with said widthwise edges extending therefrom to points 84 and 85, thus to cover approximately two-thirds of the face-side area of the card from its rear lengthwise edge for the full cardpack card length, and wherein from points 84 and 85 respectively, widthwise edges taper inwardly toward the front to meet fore lengthwise edge 83 at each of its sides in a point in which the end portions 94 and 95 are, as shown in FIG. 15, flush with ceiling 86.

**Design Concept C of Kinetic Card Viewing Device
Provided with Means for Commanding Selected
Periods of Time Interval Dwell**

Design concept C is derived from design concept B, with the addition of means for commanding selected periods of card dwell, in accordance with the specifications presented herewith, together with the illustrations supporting them, given in FIGS. 18, 19 and 20, as follows:

a. FIG. 18 presents a sectioned view of the upper part of the device from the front, showing means for selecting and implementing periods of time interval dwell;

b. FIG. 19 presents a sectioned view of the upper part of the device from the side showing means for selecting and implementing periods of time interval dwell;

c. FIG. 20 presents a flow chart of the principal operational functions of the device.

Except for the inclusion of reference 39 listed in FIGS. 10 and 11, the keyed references in the illustrations given in FIGS. 18 and 19, range from 45 to 65 inclusive, as follows:

39 Duct of card passageway means;

45 Side wall of device on which time interval setting means are mounted;

46 Pointer knob of timer setting means (outer shell of knob setting zeroing motor);

- 46A Switching contact points on pointer knob of timer setting means;
- 47 Pointer indicator (arrow) on pointer knob;
- 48 Timer time interval scale;
- 5 49 Knob setting zeroing motor (clad in pointer knob of timer setting means 46);
- 50 Knob setting means motor shaft;
- 51 Wall in which knob setting motor shaft 50 and shaft 58 are mounted;
- 10 52 Pilot card window;
- 53 Pilot card switch;
- 54 Timer motor;
- 55 Spur pinion on timer motor drive shaft 55A;
- 15 55A Timer motor drive shaft on which spur pinion 55 is mounted;
- 56 Driven spur gear on gear shaft 58;
- 57 Time reckoning switching discs;
- 58 Shaft on which driven spur gear 56 and time reckoning switching disc 57 are mounted;
- 20 59 Zero position switching post;
- 60 One of the time interval switching positions in switching disc 57;
- 61 Zero position switch in switching disc 57;
- 62 Wall between time reckoning switching disc 57 and timer motor gearing;
- 63 Wall separating time motor 54 from spur pinion 55 on drive shaft 55A and driven spur gear 56 on gear shaft 58;
- 30 64 Side wall of device contiguous to which timer motor 54 is located;
- 65 One of the time reckoning switching posts which connect pointer knob time setting means with time reckoning switching disc 57.
- The dwell aspect in each card drive cycle consists of a time interval deactivation aspect of the card drive means, as follows:
- a. A time interval setting means, situated on side wall 45 of device, consisting of pointer knob 46 rotatably mounted in said side wall, wherein around knob is provided stationary time interval scale 48, which consists of a series of time interval indications for effecting a time interval setting, by rotating knob to the position in which pointer (arrow) 47 thereon is opposite to a desired indication for which period of time the card drive means is set to remain deactivated in a card drive cycle;
1. Wherein the time interval setting means is arranged to reset automatically to the zero position upon the stoppage of the device when the playing of a face-side of the cards in the pack has been completed, said stoppage being effectuated through motor means 49 designed to rotate within an arc of less than 360°, with electro-mechanical means provided to effect its stoppage in the zero position, said motor means being stably mounted to knob, with drive shaft thereof 50 mounted in wall 51 so as to effect the rotation of motor means with knob held firmly in said wall, with said motor means connected to a circuit which connects to pilot card switch 53 which when closed energizes the circuit element connecting to said motor means to effect the rotation of the knob to the zero position;
- b. Timer motor 54, in coordination with intermediate transmission means, effects alternately in each revolution of time reckoning switching disc 57 a time-referenced speed and a high speed movement thereof, through spur pinion 55 on motor drive shaft 55A and driven spur gear 56 on shaft 58;

c. Switching means for zero contact position for the time interval deactivation aspect of the card drive means consists of zero position post 59 for the conveyance of current to the switching contact point in the zero contact position in time reckoning disc, said position being in perpendicular alignment with the zero position on time interval scale 48, with the switching effected as time reckoning switching disc successively rotates clockwise through its zero position;

d. The switching means for each of the time interval positions on the time interval scale connect to switching contact points 46A on pointer knob outer shell 46 along its periphery with a post provided for each time interval indication established, constituting a lead for carrying current from each respective switch in pointer knob 46 to the corresponding positions in the time reckoning switching disc, wherein for each setting of the pointer knob, the time reckoning switching disc provides in each revolution the stop and start switching impulses for the card drive means between which positions it remains deactivated for the period thus established for the dwell time of a card;

e. Electrical circuitry means, constituting that part of the circuitry of the card drive means provides the electrical control and operating means to effectuate the time interval deactivation of the card drive means.

Procedure of Operation of Device, Design Concept C

Operation of a device, as constituted in this design concept involving a selective time interval card dwell comprises:

a. The start of operation of the device. This is effected by rotating pointer knob 46 of timer setting means from the zero position to one of the time interval card dwell positions delineated on timer scale 48, resulting in the energizing of the specific time interval switching means for which the setting has been made;

b. Operation of the device, comprising the initial card drive cycle, as follows:

1. Energizing of forward movement aspect of card drive means;

2. Delayed energizing of circuit to which pilot card switch is connected, by means of a time-delay control, to provide sufficient time for reverse movement aspect of card drive means to have been completed and forward movement aspect of card drive means to have started thus for card drive nut 30 to have moved pilot card a sufficient distance from its switching position so as not to be affected by it;

3. Upon completion of forward movement aspect of card drive means, said means thereupon effecting a contact with switching means resulting in the following to take place:

i. Deenergizing of the forward movement aspect of card drive means;

ii. Activation of switch to energize timer motor time-referenced speed aspect to cause time-reckoning switching disc 57 to rotate from its zero position to the position where it is stopped by the switch representing the specific time interval for which the setting has been made, in which position it deenergizes timer motor time-referenced speed aspect and energizes timer motor high-speed aspect;

iii. Timer motor high-speed aspect rotates time-reckoning switching disc to the zero position, where a switch deenergizes said timer motor

high-speed aspect, and energizes reverse movement aspect of card drive means;

c. Each card drive cycle which follows the initial card drive cycle as presented in (b) above is a repetition thereof except that (b2) thereof is omitted;

d. The device is brought to a stop when the playing of a face-side of the cards in the pack has been completed, a point in time when the pilot card is centered in the duct of the card passageway means, thus activating the pilot card switch to activate pointer knob switch to energize knob-setting zeroing motor means 49 to rotate knob to the zero position.

Features of the device provided in the aspect of selective periods of time-interval dwell, comprise three conditions of operational control, viz.:

a. The device is not in operation when the setting of timer knob is at zero;

b. The device is in operation, and continues to be in operation, as long as timer knob is in any setting other than zero;

c. The timer knob automatically rotates to zero, and the device comes to a stop, when a face-side of the cards in the pack has been played.

A characteristic of the foregoing conditions of control is that they are vested in single means, the timer knob.

Design Concept D of Kinetic Card Viewing Device wherein the Card Drive means is Controlled by two Worm Gears of Inverted Matching Design Provided with Cam Aspects

FIGS. 21 and 22 illustrate the card drive means provided in design concept D of device, greatly enlarged, wherein;

35 a. FIG. 21 presents a partially sectioned front view of card drive means;

b. FIG. 22 presents a sectioned top view of card drive means.

Other aspects of this version of the device correspond to design concept B, as hereinbefore presented.

The keyed references in the illustrations, as given in the FIGS. numbered 21 and 22, range from 101 to 129 inclusive. They are as follows:

40 101 Clockwise rotating worm gear (shown in FIGS. 21 and 22 to left);

102 Counterclockwise rotating worm gear (shown in FIGS. 21 and 22 to right);

103 Cam aspect of worm gear 101;

104 Cam aspect of worm gear 102;

50 105 Structural aspect of device within which card drive means is situated;

106 Lower axially extending pin in worm gear 101;

107 Motor drive shaft connecting through transmission drive mechanism 108 spur gear 109 and worm gear 101 through upper gear shaft 111;

108 Transmission drive mechanism (not detailed);

109 Spur gear on upper shaft of worm gear 101;

110 Motor;

60 111 Upper shaft of worm gear 101 on which spur gear 109 is situated;

112 Lower axially extending pin in worm gear 102;

113 Upper shaft of worm gear 102 on which spur gear 114 is situated;

114 Spur gear on upper shaft 113 of worm gear 102;

115 Combination camfollower and card drive bar;

116 Cradle element, holding combination camfollower and card drive bar 115 for transverse movement;

117 Camfollower aspect of combination camfollower and card drive bar 115;

118 Aspect of structure 105 to support upper shaft 113 of worm gear 102;

119 Rod element of cylindrical bore in cradle support aspect 122 of structure 105 to hold cradle element 116 slidably arranged for longitudinal movement;

120 Card drive bar aspect of combination camfollower and card drive bar 115;

121 Recess in structure 105 for supporting card drive bar aspect 120 of combination camfollower and card drive bar 115 at outer end of card drive bar aspect 120;

122 Cradle support aspect of structure 105;

123 Tracer tooth part of card drive bar aspect 120 to move alternately in grooves 125 and 126, provided respectively to the right and to the left, within structure 105;

124 Aspect of structure 105 provided with two longitudinal grooves 125 and 126, and two transverse grooves 128 and 129, one in the upper terminus, and the other in the lower terminus, of the longitudinal grooves, to connect between them, provided respectively to the right and to the left within structure 105;

125 Longitudinal groove to guide card drive bar aspect, by means of tracer tooth part 123 on card drive bar aspect 120 in its forward movement, provided respectively to the right and to the left, within structure 105;

126 Longitudinal groove to guide card drive bar aspect, by means of tracer tooth part 123 on card drive bar aspect 120 in its reverse movement, provided respectively to the right and to the left, within structure 105;

127 Card contact part of card drive bar aspect 120;

128 Upper transverse groove (counterpart to lower transverse groove 129, concealed in FIG. 21 from view by card drive bar aspect 120) for transfer of card drive bar aspect by means of tracer tooth part 123 thereon to right longitudinal groove 126 for reverse movement of card drive bar aspect, provided respectively to the right and to the left, within structure 105;

129 Lower transverse groove for transfer of card drive bar aspect by means of tracer tooth part 123 thereon to left longitudinal groove 125 for forward movement of card drive bar aspect, provided respectively to the right and to the left, within structure 105.

In this design concept, two worm gears 101 and 102 of inverted matching design are symmetrically positioned to one another, in means holding them to provide for their respective rotation in opposite directions synchronous to one another, to cause mutually between them, through a cam aspect provided in each worm gear, to effect in a card drive cycle alternately, a forward movement drive effecting the discharge of a card out of the cartridge, and a reverse movement re-sorting the card drive means to the starting position of a card drive cycle, wherein:

a. Worm gear 101, relative to its axis, in its clockwise rotation, generates in the groove aspect between two tooth aspects, a spiral constituting a cycle of movement of camfollower therein, proceeding from the starting position in the lower part of the gear, to the terminating position in the upper part of the gear, which in its final revolution generates an outwardly spiralling plan terminating in the outer periphery of the gear, to constitute its cam aspect 103;

b. Worm gear 102, relative to its axis, in its counter clockwise rotation, generates in the groove aspect between two tooth aspects, a spiral constituting a cycle of movement of camfollower therein, proceeding from the starting position in the upper part of the gear, to the terminating position in the lower part of the gear, which in its final revolution generates an outwardly spiralling plane terminating in the outer periphery of the gear, to constitute its cam aspect 104;

5 1. Wherein said worm gears 101 and 102 are rotatably held in structure 105;

i. With worm gear 101 held therein at the top shaft 111 and at the bottom by pin 106, and wherein on shaft 111 spur gear 109 is mounted, and through transmission mechanism 108, not detailed, with motor shaft 107 thereon connected to motor 110;

10 ii. With worm gear 102 held therein at the top by shaft 113 and at the bottom pin 112, and wherein on shaft 113 spur gear 114 is mounted, with the end of the shaft seated in aspect 118 of structure 105, and wherein spur gears 109 and 114 are of equal diameter, arranged to mesh with one another and in a 1:1 ratio;

15 c. Wherein combination camfollower and card drive bar 115 constitutes an interconnecting rigid structure consisting of a camfollower aspect 117 and a card drive bar aspect 120;

20 1. Wherein camfollower aspect 117 is centrally arranged between worm gears 101 and 102 in a position of mutually common perpendicular alignment to the axes of said worm gears, and arranged to move slideably for transverse movement in fork of cradle element 116, and lengthwise in rod element 119 in cylindrical bore in cradle support aspect 122 of structural aspect 105;

25 i. Wherein respectively to the right of worm gear 102 and to the left of worm gear 101, are provided each of two identical movement control means, acting coordinatively, for keeping card drive bar aspect 120 so aligned that in its forward movement it drives forwardmost card in card receptacle means into duct of card passageway means, and in its reverse movement returns to the starting position for the next succeeding card drive cycle, wherein card drive bar aspect, in each of two positions, is provided with a tracer tooth part 124 integrally connected thereto, which extends into the groove arrangement in each respective aspect 124 of structural aspect 105, wherein it is guided in groove 125 to move therein forward, and in groove 126 to move therein backward, with said grooves interconnected by an upper transverse groove 128, and a lower transverse groove 129 to provide for a sidewise changeover movement of said card drive bar aspect from one longitudinal groove to the other, thereby in operation to effect in the grooves a continuous clockwise movement of the tracer tooth part in the controlled movement of the card drive bar aspect;

30 60 65 d. Wherein cradle element 116 is slidably supported on cylindrical rod 119 held in bore in cradle support aspect 122 of structural aspect 105 to provide for the longitudinal movement of said combination camfollower and card drive bar, to effect in the alternate forward and reverse movement of said combination, the

discharge of a card out of the card receptacle means.

Design Concept E of Kinetic Card Viewing Device Accommodating Cards with Faces Bearing a Single Continuously Evolving Horizontal Band of Graphics

FIGS. 23 and 24 illustrate design concept E of device, wherein:

a. FIG. 23 presents a cross-sectional top view of device;

b. FIG. 24 presents a front view of device.

The keyed references in the illustrations as given in the figures, numbered 23 and 24, range from 151 to 158 inclusive. They are:

151 Card viewing window in device, contiguous to transparent wall in cartridge through which face-sides of cards are exposed to view;

152 Card with face thereof containing graphical effects which exemplify a characteristic application of design concept E of device;

153 Duct of card passageway means;

154 Reversible card drive motor;

155 Card drive nut;

156 Worm gear;

157 Intermediate speed regulating means (not detailed);

158 Cards in receptacle means.

Design concept E is a variant of design concept B, constituting an embodiment of the device specifically adapted for use with cards in which their faces bear graphical effects for visual recognition in a single horizontal arrangement in a continuity for unidirectional scanning, wherein for graphical effects which are to be read from left to right, the device is arranged for movement of the cards past window 151 from right to left.

The cards for use in this design concept are of relatively narrow width, providing for the placement of a single horizontal arrangement of graphical effects, which according to the use to which to be put, may comprise a single band of staff graphics of a musical composition, as shown by example in FIG. 24, or may involve a single line of type composition, or a map cast lengthwise to a narrow width of graphical effects such as for conveying the characteristics of a highway of the geological strata in a land formation.

Should an application of the device require a display constituting a wide-angle view of the graphical matter for instantaneous comprehension, a card passageway means of an effective length equal to the length of two or more cards is to be employed. It will require a corresponding number of pilot cards. Where a multiple of pilot cards is to be employed, it is desirable that the number involved is three such cards, to which the length of the card passageway means is accordingly established, requiring only that the pilot card which is between the other two pilot cards functions as the signaling means and/or the means to effect the stoppage of the device.

In this design concept, the card drive means is provided, in its adaptation to continuous motion scanning of card faces, with a reading speed forward movement aspect, and a high-speed return movement aspect, through speed regulating means located between motor 154 and card drive means. Adjustments for different reading speeds and provision for starts and stops can be met with conventional means for controlling mechanism operation.

The application of miniature D.C. motors to portable versions of the device requires consideration of their limitation for precise positioning. To compensate for the over-run characteristic of such motor requires in the forward movement of the card drive means, a slip clutch between the motor and the worm gear to disengage the motor from the worm gear, and in its reverse movement requires extension of the range for movement of the card drive means for a distance in back of the starting position of a card drive cycle within which the motor will stop, predicated on the basis of its performance as established in tests.

A variant of design concept E provides for a multiple of horizontal arrangements of graphical effects for which the cards are designed and in which the card viewing window is provided with an adjustable selection mask for exposing a desired line, to the exclusion of the other lines, of graphical effects borne in the card faces.

Design Concept F of Kinetic Card Viewing Device, an Electrically Operated Version in which a Moving Belt Provides the Card Transport means against which the Cards are held by Vacuum (Air Suction)

Design concept F presents my invention in a device wherein the card drive means consists of a belt supported on two pulleys with the cards drawn to the belt individually by vacuum (air suction).

Refer to FIGS. 25 through 32, wherein:

a. FIG. 25 presents a side view of the device, partially cross-sectioned to show interior details;

b. FIG. 26 presents a view of the device, from the position as faced by the operator, partially sectioned to show the means provided for the application of power and vacuum;

c. FIG. 27 presents a perspective view of the device showing the viewing window and the operating controls;

d. FIG. 28 presents a card in the process of entering cartridge through two-way card-flow orifice in its front wall;

e. FIG. 29-A presents a card in the process of entering cartridge through two-way card-flow orifice in its rear wall;

f. FIG. 29-B presents a card in the process of exiting cartridge through two-way card-flow orifice in its rear wall;

g. FIG. 30 presents an enlarged partially sectioned side view of device showing card in pack in cartridge, and belt for transport of cards;

h. FIG. 31 presents an enlarged partial view of device through section A—A', FIG. 30;

j. FIG. 32 presents an enlarged partial view of device through section B—B', FIG. 30.

The keyed references in the text for the illustrations as given in the FIGS. numbered 25 through 32, range from 160 to 198, inclusive, viz.:

160 Chassis of device, pointed in the illustrations to one of the walls enclosing it;

161 Card cartridge, pointed in the illustrations to one or more of the walls enclosing it;

162 Pack of cards in cartridge;

163 Card passageway aspect of structure of device;

164 Card conveyance belt;

165 Forwardmost card in cartridge;

166 Card in duct of card passageway means;

- 167 Belt alignment insert (shown in FIGS. 31 and 32);
 Reversible motor;
 169 Motor worm drive;
 170 Motor driven pulley;
 171 Card baseplane;
 172 Vacuum pump;
 173 Pulley drive shaft;
 174 Pulley axle;
 175 Pulley drive shaft journal and bearing on vacuum pump side; 10
 177 Motor drive bevel gear on pulley drive shaft 173;
 178 Spur gear pulley drive shaft to drive spur pinion 180 on vacuum pump drive shaft 179;
 179 Vacuum pump drive shaft; 15
 180 Spur pinion on vacuum pump drive shaft 179;
 181 Vacuum duct in card drive means;
 182 Vacuum supply (air suction) line;
 183 Air discharge line;
 184 Hole in belt for inlet of vacuum (air suction) to draw card against belt; 20
 185 Forward drive/stop switch control;
 186 Reverse drive/stop switch control;
 187 Card entry/exit orifice in front wall of cartridge;
 188 Card entry/exit orifice in rear wall of cartridge; 25
 189 Card ingress aspect of two-way card-flow orifice in cartridge;
 190 Card egress aspect of two-way card-flow orifice in cartridge;
 192 Card viewing window in device, contiguous to transparent wall in cartridge; 30
 194 Space below card baseplane partitioned off for holding vacuum;
 195 Pilot card signal window;
 196 Dry-cell batteries in battery chamber; 35
 197 Access means for replacing batteries;
 198 Pulley driven by motor-driven pulley 170.
 The device consists essentially of:
 a. Chassis 160, constituted of an outer wall, enveloping device except for access means to space for the insertion of cartridge 161 and window 192 to provide for the sequential exhibiting of card-face surfaces for viewing of the graphical effects borne therein; 40
 b. Card retaining and passageway means consisting of cartridge 161 composed of a card receptacle, with pack of cards 162 contained therein, with said cartridge provided with the following: 45
 1. Two two-way card-flow orifices, providing each orifice with the characteristic to accommodate, individually in succession, at one time the discharge of cards from the cartridge, and at another time the receipt of cards into the cartridge, as illustrated in FIGS. 28, 29-A and 29-B, wherein:
 i. Card-face contact surface 189 of orifice provides for the slideable movement thereon of a card by its outer face into the cartridge; 50
 ii. Card-face contact surface 190 of orifice provides for the slideable movement thereon of a card by its inner face out of the cartridge; 55
 2. Two slots are provided in the cartridge to accommodate the belt in opposite positions of said cartridge, i.e., respectively in the front wall and in the rear wall of the cartridge, to each of which a leg of the belt is aligned, with each of the slots extending in a groove across the top and bottom walls of the cartridge, thus to provide a path for the belt in which to carry a card through the two card-flow or- 60
 65

- ifices, which are two-way orifices in a device which provides for both forward and reverse movement of the cards;
 3. Card passageway means 163 is provided with duct extending therethrough of a width and height for the passage of a card, with a widthwise strip of the duct into which card extends broadened to accommodate vacuum duct with belt therein, wherein belt acts upon card for its pick-up and transport;
 c. Card transport means:
 1. Consisting of a reversible motor 168, activated by control means in an electrical circuit, to drive through transmission means provided, pulley 170 and vacuum pump 172, with pulley 170 driving pulley 198 by means of belt 164 in a belt route which extends upward from belt take-off on pulley 170, wherein:
 i. Above the card baseplane 171, belt converges on pulley 198 to which it is rotatably mounted, with a shaft element on each side of pulley axially set in the side walls of device to align pulley so that it provides a space between its cylindrical surface and the interior semi-cylindrical surface of the outer wall of card passageway means to constitute the duct aspect in the semi-cylindrical aspect of the card passageway means; and wherein belt in a position along its loop is provided with hole 184 extending therethrough across its width through which air is sucked by vacuum duct 181 from around the surface of the card, thus belt in the two parallel aspects of the loop traverses the cartridge along its front and rear wall, whereby it sweeps along the outer face-side of card exposed to hole in belt, whereupon card is drawn against the belt in the position of the hole, with belt thus holding card as belt with card move to the opposite end of the cardpack in cartridge to deliver card by way of the card passageway means to the position in which card detaches from belt to align with the cards in said opposite end of the cardpack;
 ii. Below the card baseplane belt is enclosed in a vacuumized space occupied by motor-driven pulley 170, with air extracted from said space and from the contiguous vacuum duct above the card baseplane by means of vacuum pump 172 which discharges the air through air discharge line 183;
 2. Providing respectively for the forward and the reverse movement of the cards;
 i. Wherein in the forward movement of the card transport means, the cards are drawn individually in sequence from the front of the pack through the duct of the card passageway means for their deposit in the rear of the pack;
 ii. Wherein in the reverse movement of the card transport means, the cards are drawn individually in sequence from the rear of the pack through the duct of the card passageway means for their deposit in the front of the pack.
 In a system involving the continuous movement of the belt, such as is provided in design concept F of device, the difference in time which is involved between one revolution of the belt, and the distance traversed by belt to transport a card from the front to the rear of the cardpack, is the time during which card remains stationary in window for viewing. This dwell time is a percentage of the running time of the belt in each revo-

lution proportionate to its speed, which thus can be made the basis for regulating the dwell time to meet specific requirements. Apart from the dwell time which may thus be provided, additional dwell time may be supplied through electrical control means which involve the suspension of the card transport means for such period.

The specifications of the card transport means, hereinbefore presented, are confined to one which provides for both forward and reverse movement of the cards, inasmuch as an adaptation confined to a forward movement of the cards can readily be deduced therefrom.

Adaptation of the Kinetic Card Viewing Device to Punched Card Data Processing.

The adaptation of the kinetic card viewing device embodying my invention to data processing involves indicia representing data concepts which are designed to take effect for each face of a card to the exclusion of the other face. This purpose is accomplished by means of an indicium which is in the nature of an opening in the card substance in the shape of an elongated rectangle, with the elongated aspect thereof set at an angle of 45° relative to the direction of card movement, consistently pointed in the same direction, such as from the lower left to the upper right in the face which is faced to be acted upon by sensing means provided in device, wherein the contiguous card substance establishes the confines of a switch for injection into the hole represented by the indicium to effect a connection to a data sensing circuit. An indicium for the back face comes through the card substance on the front face in the same shape except that the image is inverted relative to one which is applicable to the front face, thereby to put an indicium for the back face in sufficient disalignment to an indicium for the front face that the switch in said position is blocked from coming into registry with it when the front face is being played.

FIG. 34 shows the design of the indicia used in the cards wherein, for example, indicium 211 pointing from the lower left to the upper right is applicable to the card-face which is exposed to view, and each of the indicia 214 pointing from the lower right to the upper left is applicable to the back face which is the face which will be acted upon when the card turns over for the play of that face-side.

Design Concept G of Kinetic Card Viewing Device, Providing for the Retrieval of a Card for the Face Bearing Desired Data From Among the Cards in a Pack

Refer to FIGS. 33 through 38, wherein:

a. FIG. 33 presents a portion of the combination data retrieval selector aspect and card viewing window;

b. FIG. 34 presents a portion of a cardface in the retrieved position for viewing, with portion of the face of card which had preceded it also showing;

c. FIG. 35 presents an enlarged cross-sectional front view of the data retrieval means with each of three switches extended into indicia in card of face being retrieved as had been commanded;

d. FIG. 36 presents an enlarged cross-sectional side view of the data retrieval means with switch in an extended (closed) position;

e. FIG. 37 presents an enlarged cross-sectional side view of the data retrieval means with switch in retracted (open) position;

f. FIG. 38 presents FIG. 35 with the addition of the electrical circuit provided for sensing the indicia in the applicable cardface upon completion of the movement of the card into the position of registry in the indicia sensing and data viewing station in duct of card passageway means, with data portion of retrieved card in window for viewing, with circuit completed through switching means provided to effect the stoppage of the device.

10 The keyed references in the illustrations as given in the figures numbered 33 through 38 range from 201 to 223.

A description of the keyed references follows:

201 Alphabetical symbols in a horizontal reference strip in retrieval command selector input aspect in outer wall of card passageway means to serve as a guide in positioning symbol command positioning blocks;

202 First place symbol slide slot;

203 Second place symbol slide slot;

204 Third place symbol slide slot;

205 First place symbol command positioning block, set to symbol C;

206 Second place symbol command positioning block, set to symbol O;

207 Third place symbol command positioning block, set to symbol M;

208 Card viewing window in device, contiguous to transparent wall in cartridge through which face-sides of cards are exposed to view;

209 Alphabetical symbols borne in cardface to serve as a guide in the placement of indicia therein for registry with symbol command positioning blocks for which a corresponding guide aspect 201 is provided in retrieval command selector input aspect in outer wall of card passageway means;

210 Portion of card, showing outer face thereof, which had preceded card located in indicia sensing station;

211 Indicium in first place symbol position in card for applicable face, set to symbol C;

212 Indicium in second place symbol position in card for applicable face, set to symbol O;

213 Indicium in third place symbol position in card for applicable face, set to symbol M;

214 An indicium applicable to reverse face of card;

215 Graphical effects for visual recognition borne in cardface shown in a Greeked copy block;

216 Data retrieval command aspects (circuit elements) in outer wall 219 of card passageway means;

217 Card in indicia sensing station;

218 Inner wall of card passageway means;

219 Outer wall of card passageway means containing data retrieval command aspect 216;

220 Cavity in inner wall of card passageway means for holding extensible helical spring 221;

221 Extensible helical spring;

222 Spring-actuated data input switch;

223 Indicia sensing and data retrieval command circuit.

60 Adaptation of the kinetic card viewing device of my invention to the retrieval of a card from a pack for the data contained in one of its two faces to which the card is positioned upon retrieval, involves, relative to the means provided in design concept B, upon which this adaptation is based, the addition of retrieval means, and means otherwise provided in altered form, as follows:

a. A pack of cards in cartridge, wherein each card in each of its two faces is divided into two separate areas, viz.:

1. An area for the placement of the indicia representing the symbols in a code combination for effecting the retrieval of a card to the specific face thereof, wherein the positions in the cardface for placement of indicia are in registry with corresponding positions provided in data retrieval command aspect 216 in outer wall of card passageway means;
  - i. Each indicium is in the nature of an opening in the card substance in the shape of an elongated rectangle with the elongated aspect thereof set at an angle of 45° relative to the direction of card movement, consistently pointed in the same direction;
2. A data area, designed for registry with window 208 which provides for exhibiting the data therethrough;
  - b. A card cartridge, referred to in foregoing paragraph (a), and a card passageway means, which provide them, from cardbase of forwardmost card in pack, to cardbase of rearwardmost card in pack, a combined distance in aliquot card lengths, of no less than four such lengths, of which two of them comprise the distance thereof in cartridge;
  - c. An indicia sensing and data viewing station is provided, situated in duct of card passageway means, in the position to which card has been moved by the card drive means upon completion of its forward movement drive, in which position card remains stationary until the start of the next succeeding forward movement drive, wherein:
  - d. Contiguous to card in indicia sensing and data viewing station, in outer wall 219 of card passageway means are contained the data retrieval command aspect 216 and card viewing window 208, wherein:

1. Data retrieval command aspect 216, which is herein presented in an example which provides for 40 the retrieval of a card for the face bearing data identified by the three-place code combination COM for the term COMSAT, wherein as illustrated in FIGS. 33 and 34:
  - i. Three symbol place positions are provided 45 whereby each card for each face is separately retrievable from the cards in the pack;
  - ii. The symbols which are involved in the retrieval command aspect are the letters of the alphabet, with the cardfaces provided with the corresponding symbols in positions of registry therewith;
  - iii. The symbol combination which is involved to effect the retrieval of a card for the face containing desired data consists of three place positions, viz.: COM for the term Comsat, as set forth in 55 (d1) above, requiring three slots as follows:

First place symbol slide slot 202;
Second place symbol slide slot 203;

Third place symbol slide slot 204;

- iv. A symbol command slide block is provided for each slide slot, as follows:

First place symbol command position slide block, set to symbol C, 205;

Second place symbol command position slide block, set to symbol O, 206;

Third place symbol command position slide block, set to symbol M, 207;

2. Window 208, keyed for registry with data aspect in cardface, to exhibit the data for viewing, as per paragraph (a2);

5 d. Within the area of the face-side of card in indicia sensing and data viewing station, in inner wall 218 of card passageway means, are contained the indicia sensing means, consisting of an indicium sensor aspect (switching means), for each symbol in a series in each place position to provide for every symbol combination, with each sensor aspect located in a cavity 220 containing an extensible helical spring 221 and a switch 222, wherein switch extends into indicium when indicium is in registry with switch, thereby for switch to move into closed position therein;

10 f. The electrical means provided for the indicia sensing and data retrieval means involve, in addition to the electrical means provided in card drive means in design concept B, the following:

15 1. Indicia sensing and data retrieval command circuit 223 extending within the area of the indicia sensing and data viewing station through inner wall 218 and outer wall 219 of card passageway means, as shown in FIG. 38, wherein:

20 i. Circuit elements in symbol command positioning blocks 205, 206, 207 in outer wall 219 of card passageway means link to circuit element skirting inner wall of card passageway means to constitute circuit 223 for energizing, wherein:

ii. Card drive switching means closes the indicia sensing circuit when card drive means forward movement aspect has delivered card to the indicia sensing and data viewing station where card remains until card drive means reverse movement aspect has returned to the starting position for the next succeeding forward movement of the card drive means whereupon card drive switching means opens the indicia sensing circuit, wherein:

25 iii. In each card drive cycle, a successive cardface comes into position in the indicia sensing and data viewing station for sensing of the code combination of the indicia contained therein against the setting of the code combination in the retrieval command, until cardface with indicia matching the setting of the retrieval command comes into position into said station, which upon being sensed effects the stoppage of the device through a switch provided therefor linked to the card drive motor means, with the retrieved cardface exhibiting the data contained therein in window; whereupon device is ready to receive the next command for the retrieval of a cardface for the data contained therein.

30 Design Concept H of Kinetic Card Viewing Device with Cardfaces Programmed to Convey Recurring Capsulized Data Concepts for Display in an Illuminable Display Panel in Synchronism with the Communicable Matter Borne in Cardfaces for Display in Window for Viewing, which said Capsulized Data Concepts Serve to Augment

35 This design concept involves, relative to the means provided in design concept B upon which the adaptation is based, additional means, and means otherwise provided in altered form, as follows:

a. A card cartridge, wherein the pack of cards it contains has each of the two faces of each card divided into two separate areas, as follows:

1. A data area in registry with card viewing window, bearing communicable matter for visual recognition;

2. An area for the placement of an indicium representing a capsulized data concept for implementation in cardface to provide recurring supporting data relating to the data contained in cardface for display in viewing window, presented in (1) above, constituting a method which is extensible to each face of each card to which a selective input from among the number of capsulized data concepts provided is applicable;

i. With each indicium constituting an opening in the card substance in the shape of an elongated rectangle with the elongated aspect thereof set at an angle of 45° relative to the direction of card movement, consistently pointed in the direction;

b. A series of display panels, one for each capsulized data concept provided, each of which contains an indicator light linked to its respective indicium switch, with the graphical effects setting forth the capsulized data concept in placement within the area of applicable display panel rendered visible by said indicator light;

c. A window, keyed for registry with data portion of cardface for viewing of the data contained therein, referred to in foregoing paragraph (a1);

d. An indicium sensing and data viewing station, situated in duct of card passageway means, in the position into which card has been moved by the card drive means upon completion of the forward movement drive, in which position card remains stationary until the start of the next succeeding forward movement drive of the card drive means, providing a time interval for card dwell which includes a time delay effected by a control means, thus providing a card dwell period in which the beginning thereof provides for the sensing of the indicium in the card for the appertaining face, and the total thereof provides for the viewing of the graphical effects for visual recognition, both in the cardface exhibited in viewing window, and in the illuminated compartment in display panel;

1. Inner wall of card passageway means within the area of the indicium sensing and data viewing station contains a sensor aspect for each compartment into which display panel is divided, with each sensor aspect constituted of a cavity containing an extensible helical spring and a switch, wherein the switch, should it be the applicable one, comes into registry with indicium in card wherein through pressure of spring on switch effects the extension of the switch into indicium, thus to close the switch;

e. Electrical means, in addition to the electrical means provided in the card drive means in design concept B of device, consisting of a switch to energize and deenergize the indicium sensing circuit, and while energized, to energize the sensor aspect (switching means) and the indicator light of the applicable compartment of the display panel.

Design Concept J of Kinetic Card Viewing Device
Providing for Response Participation between Device
and User of the Device to Programmed Data-Bearing
Cards in Cartridge, Augmented by Score Registry
Means for Measuring Performance

Refer to FIGS. 39, 40 and 41, wherein:

a. FIG. 39 presents a portion of a cardface designed for communications in a dialogue style as exemplified for application in teaching;

b. FIG. 40 presents a view of the instrument panel of a device of my invention providing for cards designed for a system of data application for response participation of user, and providing score registry means for measuring performance;

c. FIG. 41 presents an enlarged view of the marginal strip of card containing the indicia, with a legend for their interpretation.

The keyed references in the illustrations are given in the figures numbered 39, 40 and 41, range from 226 to 239 inclusive. They are as follows:

226 An indicium as used in an example presented herein applicable to a cardface being played;

227 An indicium as used in an example presented herein applicable to a cardface on opposite side of cardface being played, shown superimposed on imprinted indicium placement position in cardface being played;

228 Two indicia applicable to opposite faces of a card, which register in the card substance in the same corresponding position, as shown in cardface being played;

229 Unused imprinted indicium position in cardface;

230 Upper area of a pair of areas of a learning element (LE) consisting of a question or interrogative assertion;

231 Lower area in each pair of areas of a learning element (LE) bearing three suggested response assertions to a question or interrogative assertion;

232 Unit area of a learning element (LE) comprising areas 230 and 231;

234 Selector buttons, numbered respectively 1, 2 and 3;

235 Card viewing window in device, contiguous to transparent wall in cartridge against which cardface bearing data for viewing is positioned;

236 Vertical section of cardface composed of horizontal areas containing data for viewing;

237 Score registry dial in score indicating window;

238 Marginal strip in cardface, for application of indicia, with each indicium stamped out of the card substance in the required imprinted indicium position, said indicium being in the shape of an elongated rectangle, with the elongated aspect set at an angle of 45° relative to the direction of card movement, consistently pointed in the same direction;

239 Score clearing button.

Adaptation of a device of my invention as a teaching, entertainment or game machine for response participation between user and device involves, relative to the means provided in design concept B upon which it is based, the addition of data input and response means, and score registry means, as follows:

a. A pack of cards wherein each cardface consists of two general areas, each relating to a specific card function, viz.: an area along the left margin 238, providing for the instrumentation of data inputs (responses to se-

lections exercised), and an area comprising the remainder of the cardface 236, for exhibiting data for viewing, wherein:

1. In each cardface, the area along the left margin is provided with position indications for the placement of indicia in a single vertical formation along the line of card movement, with said area subdivided into areas constituting extensions of the horizontal bands of paired areas of which the data area is composed, for the instrumentation relating to each respective band; 10

i. Wherein each separate instrumentation area relating to a dialogue action (learning element), provides three positions for indicia placement, of which one position representing the acceptable response selection, is provided with an indicium, with the other two positions left blank; 15

2. In each cardface, each horizontal band comprising a pair of areas, provides in each upper area thereof for a question or interrogative assertion, and in each lower area thereof for the presentation of three suggested response assertions, one of which constitutes the acceptable response assertion; 20

b. A window 235 in device of the dimensions of a unit area in cardface for the data to be viewed, to which the card drive means is in timed registry, thus to bring successively in a stop-and-go movement of the card, a unit area of cardface into view; 25

c. A means for exercising a selection from among three choices as provided in the lower area in a set of paired areas in cardface; 30

1. Wherein the means for exercising a selection is provided in three selector buttons 234, one opposite each suggested response assertion borne in cardface for viewing through window 235; 35

d. Score registry means, providing for the measuring of user's performance in a programmed test, as set forth in cards covering a series of questions or interrogative assertions upon which user is directed to exercise selections upon which his performance is measured against the acceptable response assertions as programmed, wherein each test comprising a series of questions or interrogative assertions starts with a perfect score, from which each unacceptable selection exercised produces a progressive reduction in the cumulative score; 40

1. Wherein a response selection made which causes selector button 234, upon being manually depressed, to light up, indicates that the selection made is the acceptable selection, thus keeping score registry dial 237 deactivated as no change in the score has resulted; 50

2. Wherein a response selection made which does not cause selector button 234, upon being manually depressed, to light up, indicates that the selection made constitutes an unacceptable selection, thus causing score registry dial 237 to be activated to bring the score to the next successively lower reading; 55

e. An indicium sensing and data viewing station, situated in duct of card passageway means, wherein contiguous to card therein, in inner wall of card passageway means, are provided three indicia sensor aspects (switching means) covering the three choices of response selections in each alternate segment of cardface relating to the exercise of a response selection, to 60

65

which the three indicia positions in the cardfaces are in registry;

1. To which card has moved upon the completion of a forward movement of the card drive means, in which position card remains stationary until the start of the next successive forward movement of the card drive means, wherein:
  2. In two such movements, constituting the completion of a dialogue (reciprocal) action, wherein the first movement involves the exposure to view of a data presentation aspect, and the second movement involving, in addition to a data presentation aspect, the applicable indicium as programmed, from among the three indicia positions provided, with said indicium in registry with the applicable sensor aspect (switching means) to effect the energizing of the circuit element relative thereto;
  - f. Electrical means, in addition to the electrical means provided in design concept B, wherein:
    1. The completion of each forward movement of card drive means delivers card by a successive segment into position of registry in indicium sensing and data viewing station, whereupon, as each alternate segment of a cardface covering a learning element is thus positioned, card drive switch energizes circuit element to energize indicium sensing switch, and in the terminating position of the reverse movement of the card drive means, said switch is deenergized, involving an interval of time during which card remains stationary in said station for segment to be viewed in window;
      - i. The applicable selector button, one of three selector buttons provided, is arranged to respond to the acceptable selection as implemented in the indicium provided, which upon being manually depressed, results in indicator light to illuminate;
      - ii. One of the two selector buttons of the three selector buttons provided, neither one of which constitutes the selection for the acceptable response, fails to illuminate its respective indicator light when manually depressed, results in a bypass switch connected to each of the selector buttons to energize an electro-magnet to actuate mechanical means to effect a reduction in the score to the next lower cumulative score as displayed in dial of score registry means;
    2. A score clearing switch, which when manually depressed, energizes an electro-magnet to actuate mechanical means to clear score registry means for starting the scoring for the next successive test.

The presentation of design concept J given herein is based on an example of its application involving multiples of reciprocal data concepts covered in each face-side of each card. Two simpler applications for adaptation in device involve for each set of reciprocal data concepts:

  - a. An entire face-side of a card;
  - b. Two separate face-sides of two cards;

a. FIG. 42 is a side view of upper part of device, with facility in attachment thereto in fully extended position, as used when carrying the device;

b. FIG. 43 is a front view of upper part of device with facility in attachment thereto, relative to the side view presented in FIG. 42;

c. FIG. 44 is a side view of upper part of device, with facility in attachment thereto, adjusted into a position to put the device in an inclined position for its use as for reading;

d. FIG. 45 is a perspective view of device, with facility in attachment thereto, placing device in an inclined position on a horizontal surface such as a tabletop for its use as for reading;

e. FIG. 46 is a side view of upper part of device, with facility in attachment thereto, in retracted position for convenience in storing device;

f. FIG. 47 is a partial front view of upper part of device, with facility in attachment thereto in retracted position, projected relative to side view presented in FIG. 46;

g. FIG. 48 is a cross-sectional side view of upper part of device, with facility in attachment thereto in retracted position projected relative to views presented in FIGS. 46 and 47.

The keyed references in the illustrations as given in the figures, numbered 42 through 48, range from 250 through 269 inclusive. They are as follows:

250 Enveloping wall extending all around device between its two side walls 251, 252;

251 Right side wall of device, relative to position in FIG. 43;

252 Left side wall of device, relative to position in FIG. 43;

253 Right side support member aspect, relative to position in FIG. 43;

254 Left side support member aspect, relative to position in FIG. 43;

255 Handle bar aspect;

256 Flat surface of butt end in each side support member aspect 253, 254;

257 Slot in each side support member aspect 253, 254 (each identified by the same reference number 257);

258 Bolt extending widthwise through upper part of device;

258A head of bolt;

259 Nut at threaded end of bolt;

260 Bolt-shank enclosing means;

261 Card passageway means with duct 261A extending therethrough;

262 Cleat aspect in each side wall of device (each identified by the same reference number 262), integral to device, for perpendicular alignment of side support member aspects to device;

263 Cleat aspect in each side wall of device (each identified by the same reference number 263) integral to device, for lengthwise alignment of side support member aspects to device;

264 A pair of steel inserts, one of which is a magnet, provided on each side

265 of device, between a side support member aspect 253, 254, and cleat aspect 262, 262, to effect a magnetic hold between them;

266 A pair of steel inserts, one of which is a magnet, provided on each side

267 of device, between a side support member aspect 253, 254, and a cleat aspect 263, 263, to effect a magnetic hold between them;

268 Fluted channel in enveloping wall 250 of device widthwise along its apex for seating handle bar aspect 255, effected when side support and handle bar assembly 269 is in its fully retracted position;

269 Side support and handle bar assembly, consisting of side support member aspects 253, 254, and handle bar aspect 255.

Three positions of adjustment are provided for the combination carrying handle and use support facility in its attachment to device, as follows:

a. Lengthwise extended, as used when carrying the device, shown in FIGS. 42 and 43;

b. Perpendicularly positioned, for placement of assembly on a horizontal surface such as a tabletop to support device so that the viewing window is inclined toward the user as for reading, shown in FIGS. 44 and 45;

c. Lengthwise retracted, providing a convenient way for storing device, shown in FIGS. 46, 47 and 48.

To install combination carrying handle and use support facility on device:

a. Affix two side support member aspects 253, 254, to handle bar aspect 255, at each of its two ends, thus to constitute combination side support and handle bar assembly 269;

b. Affix to each side wall of device;

1. Cleat 262;

2. Cleat 263;

c. Affix below apex of inner wall of card passageway means 261:

1. Bolt-shank enclosing means 260.

d. Position side support member aspects 253, 254, of assembly 269 against side walls 251, 252, of device, while said aspects are held lengthwise retracted, with their respective slots superimposed on hole in device so as to locate hole within the upper area of the slot;

e. Push bolt 258 through hole in device, with side support member aspects held through their slots on bolt shank between bolt head 258A and nut 259 and side walls 251, 252, of device, and fasten nut 259 to bolt 258.

For details in the application of the steel inserts to the cleat aspects and side support member aspects, refer to 264, 265, 266, 267, in the listing of the keyed references.

It is to be understood that the present invention as objectified in a kinetic card viewing device is not limited to the means presented in the specifications, which by example include the use of a worm drive and a vacuum card gripper belt drive, and that the drive could be provided by a ratchet actuated by a reciprocating lever.

Although I have described my invention with a certain degree of particularity, it is understood that the present disclosure has been made only by way of fundamental design concepts and examples, and that others can, by applying current knowledge, readily adapt the invention for various applications without omitting features which fairly constitute essential characteristics of the generic and species aspects of my contribution to the art, and therefore, such adaptations should and are intended to be comprehended with the meaning and range of equivalence as hereinafter claimed.

What is claimed as new and desired to be protected by Letters Patent is:

1. A device with a card receptacle means which contains a pack of cards, said receptacle being bounded by six rectangular walls which define an enclosure, the upper wall of said enclosure is provided with a card exit slot and a card entry slot in substantially parallel alignment, respectively, with the front and rear cards in said receptacle means; 5

the device includes a card passageway means with duct therein for the transfer of the cards individually in sequence from the front to the rear of the receptacle means, said card passageway means being seated on said upper wall of the receptacle means by its two ends of a cross-sectionally inverted U-shaped configuration, to which each terminus of said duct extends wherein it meets a slot in said 15 upper wall of the receptacle means;

a card apart from the cards in the pack is provided and is located in the duct of the card passageway means preceding the start of operation of the device, upon operation of the device said card abuts 20 and moves sequentially with the cards of the pack; the wall of the receptacle means facing the front card of the cards in the receptacle means having a slot centered widthwise thereto for the card's full 25 length and extending linearly therefrom such distance below the baseplane of the cards therein into the lower wall, to provide in a forward movement of a manually actuated card drive means for card to be expelled from the receptacle means, a card pusher element of said card drive means extends through said slot into the receptacle means to the depth at which it effects contact with the baseplane of said front card to the exclusion of the other cards in said receptacle means;

whereby the action of the card pusher element expels a card from the receptacle means, said last mentioned card bears against the card which is occupying the duct to move it therefrom through the card entry slot of the receptacle means from whence it is deposited in the receptacle means to become the backmost card of the cards therein, the wall of the receptacle means contiguous to the outer face of said backmost card constitutes the window for viewing the card, said window being composed of transparent material with its interior 40 surface contoured so as to guide the incoming card, so that upon completing its entry into the receptacle means further means offsets said incoming card from said wall to provide a space between itself and said wall for entry of the next succeeding card; 45

a card drive retaining means attached adjacent to the wall of the receptacle means facing the front card of the cards in the receptacle means and structurally stabilized relative to said wall provides for a 50 push/pull block adapted to be slid forward and backward by respectively pushing and pulling on said block aspect manually each way between two anchor blocks positioned on said card drive retaining means, to effect respectively the discharge of a card out of the receptacle means, and the restoration of the card drive means to the starting position of a card drive action, wherein said anchor blocks provide between them a measured distance to which the card drive means is held.

2. A device including a cartridge to effect therebetween the circulation of the cards contained in said cartridge for their sequential viewing in said cartridge: 65

the cartridge comprises in combination a receptacle means and a pack of aligned cards contained in said receptacle means;

the receptacle means is in the shape of a hexahedron bounded by six rectangular walls comprising a front wall facing the outer face of the front card of said pack of cards, a rear wall of transparent material constituting a window for viewing individual card faces, an upper wall, a lower wall and two side walls, said walls being contiguous to the four ends of the cards;

the upper wall is provided with a card exit slot and a card entry slot in substantially parallel alignment respectively with the front and rear cards in the receptacle means;

the front wall is in two parts, separated from one another by a slot centered widthwise to its length, of a width to accommodate slideably a card pusher element of a card drive means, said slot extending therefrom linearly for such distance below said front wall into the lower wall to provide the required range for the card pusher element of the card drive means to engage a card along its end contiguous to the lower wall and thereby eject said card out of the receptacle means;

the rear wall is provided in its interior surface with a protrusion to offset therefrom the card completing its movement into the receptacle means so as to leave a space between itself and the wall for entry of the next succeeding card;

the cards of the pack are of such dimensions as to provide an amount of clearance between their ends and the respective walls of the receptacle means contiguous thereto that the cards do not bind against said walls, and the pack comprises such quantity of cards that continual pressure is maintained by the cards against the front and rear walls of the receptacle means;

the cards are of such thickness that only one card at a time can pass through the card exit slot and the card entry slot of the receptacle means, and that only one full card at a time can be accommodated in the duct of the card passageway means;

both faces of each card in the pack are utilizable for application of graphical effects for visual recognition which are on the one face up-side-down relative to those on the face reverse thereof;

the device comprises in combination:

enclosing walls for holding the cartridge stably in position for operation, and means to render the space into which cartridge fits easily accessible for its insertion and removal;

a card passageway means with duct therein for the slideable transfer of the cards individually in sequence from the front to the rear of the receptacle means, said card passageway means being in such position that a cartridge is insertable in the device said card passageway means is located on said upper wall of the receptacle means by its two ends of a cross-sectionally inverted U-shaped configuration to which each terminus of said duct extends wherein it meets a slot located in said upper wall of the receptacle means;

the length of the cards in the receptacle means is substantially equal to the length of the duct in the card passageway means, before the start of operation of

the device a card in said duct abuts both the front and rear cards in the receptacle means; a card apart from the cards in the pack is provided, and located in the duct of the card passageway means preceding the start of operation of the device with the cartridge in position in the device with all of the cards of the pack intact, upon operation of the device said card apart moves sequentially with the cards of the pack, thus upon the completion of the return of the cards of the pack 10 into the receptacle means, said card apart again occupies the duct of the card passageway means, means permitting the removal of the cartridge with the cards of the pack intact, from the device; the card pusher element of the card drive means extends vertically through slot in front wall of receptacle means to the depth at which it underlies the bottom portion of the front card to the exclusion of the other cards in the receptacle means, whereupon in a card drive action said pusher element 20 bears against said rear end of card to eject card

from said receptacle means; and wherein said card pusher element is provided with a sloping face extending rearward from the apex of its card contact fact to effect an unobstructed return movement of the card pusher element to the starting position of a card drive action; a card drive retaining means constituting a rigid extension of the wall of the device contiguous to the front wall of the receptacle means, provides for a push/pull block of card drive means to be slid thereon manually forward and backward by respectively pushing and pulling on said block each way between two anchor blocks positioned on said card drive retaining means, to effect respectively the discharge of a card out of the receptacle means, and the restoration of the card drive means to the starting position of a card drive action, wherein said anchor blocks provide a measured distance to which the card drive means is held.
